VAPORACKUMULATOR, OF STOCKHOLM, SWEDEN.

SULFITE-BOILER PLANT.

1,292,080.

Specification of Letters Patent.

Patented Jan. 21, 1919.

Application filed February 24, 1917. Serial No. 150,746.

To all whom it may concern:

Be it known that I, JOHANNES KARL RUTHS, doctor-engineer, subject of the King of Sweden, residing at Djursholm, in the

5 Kingdom of Sweden, have invented certain new and useful Improvements in Sulfite-Boiler Plants, of which the following is a specification.

In the operation of sulfite boilers a certain amount of steam is usually passed through the filled boiler before the actual boiling takes place. The carrying out of this process, called steaming process, requires about 45 minutes. During the steaming the wood chips sink together and the boiler may therefore be filled once more after the steaming has been finished, said subsequent filling requiring about 10 minutes. Eventually the steaming is repeated 20 for about 15 minutes. As the time for the first filling usually amounts to 20 minutes, altogether about 90 minutes are thus required for filling and steaming.

The present invention relates to an arrangement whereby the time for steaming and filling is reduced to a minimum. A short steaming time is, evidently, of great importance for obtaining the greatest possible output per boiler which increases according as the steaming time decreases. Hitherto, however, a rapid steaming has been impossible with regard to the steam boiler plant in view of the fact that the steaming requires a large amount of steam which must be distributed over a comparatively long time in order not to force the steam boiler plant. A forced working of the steam boilers would greatly reduce the pressure of the steam and cause a disturbance in the operation of engines, etc., operated from the steam boilers. In addition the boiler plants hitherto known have the disadvantages incident to an irregular firing and which are inevitable even with the comparatively long steaming time now used.

According to my invention, however, a considerable shortening of the steaming period is made possible without a forced working of the steam boiler plant being necessary. On the contrary, the boiler plant is relieved to a great extent of variations in load and pressure and the economy of the total plant is thereby increased.

This advantage is obtained chiefly by the arrangement that the steam for the steam-

ing is not led directly from the steam boilers to the sulfite boilers but first to a steam accumulator which in turn supplies steam when required.

By this arrangement the flow of steam from the steam boilers to the accumulator may be regulated so as to obtain a constant flow, corresponding to the distribution of the total amount of steam required for the steaming over the whole period between two steaming operations. The steam boilers are thereby subjected to a more uniform pressure than previously in spite of the steaming period being considerably shorter. In certain cases the charging steam may even be supplied particularly during the times when the steam boilers are only slightly loaded. In this way the accumulator may balance to a considerable extent also variations caused by other loads.

The accompanying drawing shows diagrammatically an arrangement according to my invention. The steam boilers A supply steam to the steam conduit L. Through the conduit G and the control valve V a uniform amount of steam balanced according to the total load is flowing to the accumulator B. During the steaming periods steam is then supplied from the accumulator through the pipe R to the sulfite boiler C.

In addition to the shortening of the steaming time obtained by the insertion of an accumulator between the steam boilers and the sulfite boiler or boilers in the way described a shortening of the total time required for steaming and filling may also be effected by a modified steaming process consisting in admitting the steam for the steaming to the boiler C at the lower part thereof instead of the upper part as hitherto usually done. The boiler is filled as before with chips but the steam for the steaming is admitted at about the same time while the boiler is open so that the subsequent-filling and the filling are carried out without interruption during the steaming. Thus, the filling and subsequent-filling need not be carried out in different stages and the steaming and filling process therefore do not require any longer time than that during which the steam is supplied to the boiler.

I claim as my invention:

In sulfite boiler plants the combination with the steam generator and the sulfite boiler, of a steam accumulator arranged be-

- tween the said generator and boiler, a steam conduit from the said generator to the said accumulator, a second steam conduit from the latter to the said boiler, and a means in
5 the first steam conduit for controlling the flow of steam from the said generator to the said accumulator.

In testimony whereof I affix my signature in presence of two witnesses.

JOHANNES KARL RUTHS.
